CLAIM

The ornamental design for a display screen or portion thereof with graphical user interface, as shown and described.

DESCRIPTION

FIG. 1 is a front view of an embodiment of a display screen or portion thereof with graphical user interface; FIG. 2 is a front view of a second embodiment thereof; and, FIG. 3 is a front view of a third embodiment thereof. Broken lines shown in FIGS. 1-3 of the display screen or portion thereof with graphical user interface form no part of the claimed design.

1 Claim, 2 Drawing Sheets
